Inventor

S. B. Terry

S. B. TERRY, OF WATERBURY, CONNECTICUT.

Design No. 3,464, dated April 27, 1869.

DESIGN FOR A CLOCK-CASE.

The Schedule referred to in these Letters Patent and making part of the same.

To all whom it may concern:

Be it known that I, S. B. TERRY, of Waterbury, in the county of New Haven, and State of Connecticut, have invented a new and improved Design for Clock-Cases; and I do hereby declare that the following is a full, clear, and exact description thereof, which will enable others skilled in the art to make and use the same, reference being had to the accompanying drawing, forming a part of this specification.

The drawing represents a perspective view of my new design for clock-cases.

This invention relates to a new design for clock-cases, and consists in a round-headed case A, which has a circular sash hinged to its front side, the edge of which forms a moulded ring, B, as shown, in con-

nection with the projecting base C, provided with bevelled steps, a c, separated by a plain portion, b, the space upon the front of the case, between the bevelled step c and the moulded ring B, being left perfectly plain, as shown in the drawing.

Having thus described my invention, What I claim as new, and desire to secure by Letters Patent, is—

The design for a clock-case herein set forth and shown.

S. B. TERRY.
